UNITED STATES PATENT OFFICE.

GEORGE W. HOWES, OF DOWAGIAC, MICHIGAN, ASSIGNOR TO ESTATE OF P. D. BECKWITH, INC., OF DOWAGIAC, MICHIGAN.

HEATING-STOVE.

1,106,871.

Specification of Letters Patent. Patented Aug. 11, 1914.

Application filed February 19, 1914. Serial No. 819,621.

To all whom it may concern:

Be it known that I, GEORGE W. HOWES, a citizen of the United States, residing at Dowagiac, Michigan, have invented certain 5 new and useful Improvements in Heating-Stoves, of which the following is a specification.

This invention relates to improvements in heating stoves.

10 The main object of this invention is to provide in a heating stove an improved structure whereby the air is effectively circulated and moistened.

15 Further objects, and objects relating to structural details, will definitely appear from the detailed description to follow.

I accomplish the objects of my invention by the devices and means described in the following specification.

20 The invention is clearly defined and pointed out in the claims.

A structure which is a preferred embodiment of my invention is clearly illustrated in the accompanying drawing forming 25 a part of this specification, in which:

Figure I is a rear elevation of a stove structure embodying the features of my invention. Fig. II is a detail vertical central section from the front to the rear, the 30 walls and parts being shown more or less conventionally. Fig. III is a detail vertical transverse section on a line corresponding to line 3—3 of Fig. II. Fig. IV is a detail horizontal section through the flues 35 on a line corresponding to line 4—4 of Fig. II. Fig. V is a rear perspective view of the water pan. Fig. VI is a detail horizontal section through the air circulating flue above the water pan, taken on a line 40 corresponding to line 6—6 of Fig. II.

In the drawing similar reference characters refer to similar parts throughout the several views, and the sectional views are taken looking in the direction of the little 45 arrows at the ends of the section lines.

Referring to the drawing, the outer walls or body 1 of the stove may be of any suitable design provided with doors and suitable open work, not here illustrated.

50 The body is supported upon a suitable base 2 having legs 3. In the upper part of the combustion chamber 4 is a magazine 5 and below the magazine the fire pot 6. At the top of the fire pot is a flange 7 separating the combustion chamber 4 from

the fire pot chamber 8 below the flange. Below the chamber 8 is an ash pit 9. At the top of the ash pit is a flange 10 coacting with the walls of the ash pit to form a partition across the stove, see Fig. III. The 60 side walls 9' of the ash pit are spaced from the side walls of the stove forming flue chambers 11 on each side of the ash pit.

The down draft flues 12 which open into the combustion chamber at 13 are adapted 65 to carry the gases from the combustion chamber to the rear ends of these flue chambers 11 into which they deliver. Below the ash pit are vertical partitions 14 which form a central flue 15 connected with both the 70 flue chambers 11 at its front end and delivering to the smoke delivery flue 16 at its rear end. The smoke delivery flue 16 is centrally disposed relative to the down draft flues and its inner wall 17 is spaced 75 from the rear wall of the stove body to provide an air circulating flue 18 between the down draft flues, the rear wall of the stove body and the delivery flue. The circulating flue has an inlet opening 19 at 80 its lower end and a discharge or outlet 20 at its upper end, the outlet being preferably at the top of the stove and provided with a collar 21 so that a pipe may be attached if desired to conduct the heated air to a 85 room other than that occupied by the stove, otherwise the circulating flue discharges into the room occupied by the stove.

The lower end of the delivery flue 16 is branched to embrace the inlet portion 19 90 of the circulating flue 18. The lower end 19' of the front wall of the circulating flue being extended to the bottom of the stove, see Figs. II and III.

The inlet opening is provided with a grid 95 22 removably retained by the button 23. The flue top wall 24 is common to the down draft and delivery flues and adapted to receive the water pan 25. This water pan is preferably U-shaped and of such size that its 100 rear wall constitutes a part of the front wall of the air circulating flue, that is, the air circulates through the flue against it. The top wall is provided with a flange 26 at its outer edge which serves to locate the 105 water pan and also the removable wall section 27 of the circulating flue. This wall section rests upon the top wall 24 of the flues on the outside of the flange 26 and is retained by any suitable means. The remov- 110

able wall is provided with an opening 29 above the pan and with a grid 30 which can be removed for filling the pan.

5 The water pan being positioned in the circulating flue effectively moistens the circulating air and it being positioned on the top wall of the flues is well heated to supply the desired amount of moisture.

10 By arranging the parts as described, practically all of the wall surface of the stove is utilized for radiation and a considerable amount of heat units which would otherwise escape through the smoke flue are utilized. The flues and flue chamber are of considerable capacity so that they, in effect, 15 constitute radiating drums, and opportunity is given for the radiation of the heat from the gases of combustion on their passage to the delivery opening of the smoke delivery flue. The air passing through the circulating flue contacts with the rear wall of the fire chamber which forms the front wall of the flue and with the inner walls of the down draft and smoke delivery flues and 20 becomes well heated and thus adds greatly to the radiating capacity of the stove.

It is found, in practice, that very little of the heated air circulating through the circulating flue passes out of the opening 29 30 in the wall section 27, but that the heated and moistened air is mainly discharged through the outlet 20 at the top of the flue.

I have illustrated and described my improvements, aside from the conventional 35 form in which certain parts are shown in detail, in the form in which I have embodied the same in practice. I have not attempted to illustrate or describe various modifications which I contemplate as I believe the 40 disclosure made will enable those skilled in the art to which this invention relates to embody or adapt the same as may be desired. I desire, however, to be understood as claiming my improvements specifically in the 45 form illustrated as well as broadly within the scope of the appended claims.

Having thus described my invention what I claim as new and desire to secure by Letters Patent, is:

50 1. In a heating stove, the combination of a fire chamber, a smoke delivery flue having a lateral delivery opening, a pair of spaced down draft flues having delivery connections with the lower end of said smoke delivery flue, said flues having a top wall common to all and provided with an upwardly 55 projecting flange at its outer edge, an air circulating flue between said down draft and delivery flues and the fire chamber wall, said 60 circulating flue being extended above said flues and having a delivery opening at its upper end and an inlet opening at its lower end, a removable outer wall section for said 65 circulating flue resting upon said flue top wall on the outer side of its said flange, and

a U-shaped water pan arranged within said air circulating flue to constitute a part of the front wall thereof, said pan being arranged on said flue top wall within said flange thereof, there being an opening in 70 said removable wall section above said pan but below the delivery opening of the circulating flue.

2. In a heating stove, the combination of a fire chamber, a smoke delivery flue having a lateral delivery opening, a pair of spaced down draft flues having delivery connections with the lower end of said smoke delivery flue, said flues having a top wall common to all, an air circulating flue between 80 said down draft and delivery flues and the fire chamber wall, said circulating flue being extended above said flues and having a delivery opening at its upper end and an inlet opening at its lower end, a removable outer wall section for said circulating flue, and a water pan arranged within said air circulating flue to constitute a part of the front wall thereof, said pan being arranged on 85 said flue top wall, there being an opening in said removable wall section above said pan but below the delivery opening of the circulating flue.

3. In a heating stove, the combination of a fire chamber, a smoke delivery flue having a lateral delivery opening, a pair of spaced down draft flues having delivery connections with the lower end of said smoke delivery flue, said flues having a top wall common to all and provided with an upwardly 95 projecting flange at its outer edge, an air circulating flue between said down draft and delivery flues and the fire chamber wall, said circulating flue being extended above said flues and having a delivery opening at its upper end and an inlet opening at its lower end, a removable outer wall section for said circulating flue resting upon said flue top wall on the outer side of its said flange, and a U-shaped water pan arranged within said 100 air circulating flue on said flue top wall, within said flange thereof.

4. In a heating stove, the combination of a fire chamber, a smoke delivery flue having a lateral delivery opening, a pair of spaced down draft flues having delivery connections with the lower end of said smoke delivery flue, said flues having a top wall common to all, an air circulating flue between 115 said down draft and delivery flues and the fire chamber wall, said circulating flue being extended above said flues and having a delivery opening at its upper end and an inlet opening at its lower end, a removable outer wall section for said circulating flue, and a water pan arranged within said air 120 circulating flue on said flue top wall.

5. In a heating stove, the combination of a fire chamber, a smoke delivery flue having a lateral delivery opening and a top adapted 125

to receive a water pan, a pair of spaced down draft flues having delivery connections with the lower end of said smoke delivery flue, an air circulating flue between said down draft and delivery flues and the fire chamber wall, said circulating flue being extended above said flues and having a delivery opening at its upper end and an inlet opening at its lower end, a removable outer wall section 5 for said circulating flue above said delivery flue, and a water pan arranged on said delivery flue top wall within said air circulating flue, there being an opening in said removable wall section above said pan but 10 below the delivery opening of the circulating flue.

6. In a heating stove, the combination of a fire chamber, a smoke delivery flue having a lateral delivery opening and a top adapted 20 to receive a water pan, a pair of spaced down draft flues having delivery connections with the lower end of said smoke delivery flue, an air circulating flue between said down draft and delivery flues and the fire chamber wall, 25 said circulating flue being extended above said flues and having a delivery opening at its upper end and an inlet opening at its lower end, and a water pan arranged on said delivery flue top wall within said air circulating flue.

7. In a heating stove, the combination of a 30

fire chamber, a smoke delivery flue, a pair of spaced down draft flues having delivery connections with the lower end of said smoke delivery flue, an air circulating flue between 35 said down draft and delivery flues and the fire chamber wall, said delivery flue being extended above said flues and having a delivery opening at its upper end and an inlet opening at its lower end, and a water pan 40 arranged within said air circulating flue above said delivery flue, all coacting for the purpose specified.

8. In a heating stove, the combination of a fire chamber, a smoke delivery flue, a pair 45 of spaced down draft flues having delivery connections with the lower end of said smoke delivery flue, an air circulating flue between said down draft and delivery flues and the fire chamber wall and having a delivery 50 opening at its upper end and an inlet opening at its lower end, and a water pan arranged within said air circulating flue, all coacting for the purpose specified.

In witness whereof, I have hereunto set 55 my hand and seal in the presence of two witnesses.

GEORGE W. HOWES. [L.S.]
